United States Patent Office

Des. 228,481
Patented Oct. 2, 1973

228,481

BASE FOR BATHROOM FIXTURE OR THE LIKE

Willard H. Sahloff, Bridgeport, Conn., assignor to Handy-Andy Specialty Co., Inc., New York, N.Y.

Filed Feb. 3, 1972, Ser. No. 223,405

Term of patent 3½ years

Int. Cl. D6—06; D8—08
U.S. Cl. D6—86

FIG. 1 is a front elevational view of a base for bathroom fixture or the like showing my new design.

FIG. 2 is a rear elevational view thereof.

FIG. 3 is a bottom plan view thereof.

I claim:

The ornamental design for a base for bathroom fixture or the like, as shown.
